UNITED STATES PATENT OFFICE.

SPENCER C. CARY, OF BROOKLYN, NEW YORK; ALBERT A. HOVELL, EXECUTOR OF SAID SPENCER C. CARY, DECEASED, ASSIGNOR TO CARY MANUFACTURING CO., OF BROOKLYN, NEW YORK, A CORPORATION OF NEW YORK.

IMPLEMENT FOR BINDING SHIPPING PACKAGES.

Application filed February 18, 1921. Serial No. 446,034.

This invention is an implement operable for applying a binder under tension to a shipping package of one form or another, usually a box, crate or shoo.

5 In this art it is desirable to compress the components of a package in order to preclude the contents of the package from disrupting said package as well as to enable the package to withstand rough usage in 10 transporting and handling the same. It has been the practice ordinarily to bind a package by applying thereto a band composed of a flat metal strap nailed to the case or by a wire the ends of which are united; but as a 15 rule the strap or wire is not under tension with a view to compressing the components of the package so as to add stability thereto.

According to the invention, a wire binder is used, said wire binder being provided with 20 a shoulder of one form or another, and during the operation of applying tension to said binder, the shoulder thereof retains said binder in position relatively to the tensioning implement and to the package. The 25 shoulder on the wire resists the tendency of said wire to pull out of position during the operation of applying tension to said wire in order for the wire under tension to compress the components of the package, it 30 being essential that the wire shall be stretched into tight engagement with the walls of the package: in fact, the tension imparted to said wire binder is such as to embed said wire into the material of the package at the 35 corners thereof, as a result of which the wire is retained against displacement upon the package and it is not necessary to use staples or other fixtures for holding the said wire against pulling off the package, parti- 40 cularly in case the wooden walls of the package should shrink after the application of the binder.

A shoulder is provided on the binder at a suitable point and in one embodiment of the 45 invention, two shoulders are provided at separated points on the wire, the said shoulders performing the function primarily of precluding the wire during the stretching operation from displacement with respect 50 to the tensioning means.

Provision is made for applying tension to the shouldered wire at two distinct stages. The wire is passed or looped around the package, and it is stretched so as to initially

take up slack or to draw the wire taut and 55 by a continuation of this operation to apply to said binder such tension as will draw the binder tightly into contact with the package, the tension so applied operating to compress 60 the package and to embed the wire into the material of the package, at the corners thereof. This is the first stage of the tensioning operation, and subsequently thereto said wire binder is additionally tensioned by 65 twisting the crossing end portions at a point intermediate the two gripping points, whereby said binder is ultimately placed under strain throughout its length so as to take up the undesirable slack due to the elevation 70 of said binder relatively to the surface of the shipping package, which elevation of the binder is occasioned by the gripping contacts of the stretcher with the binder.

It is to be understood that the operation of 75 initially placing tension on the binder is performed by mechanism one embodiment of which employs a plurality of grippers wherein the respective end portions of the wire binder are secured, to effect which engagement of the binder with the grippers 80 it is necessary for a portion of the wire to be positioned free from contact with the surface of the shipping package and which displacement of the binder relatively to the package will, on the removal of the grippers, 85 permit a certain amount of slack to exist in the binder, ultimately tending to decrease the tension initially applied to said binder.

With a view to placing additional tension 90 on the binder for taking up the slack which ordinarily would exist upon the removal of the initial tension or stretching means, I have associated with said stretching or initial tension means a twisting mechanism, the same being positioned for action upon the 95 crossing end portions of the binder, which twisting mechanism acts to twist said crossing end portions of the binder directly together, thereby uniting said end portions and reducing the effective length of the binder intermediate the gripping points, as a result of which the undesirable slack occasioned by spacing the binder relatively to the surface of the package is taken up and 100 said binder as an entirety is placed under 105 tension throughout the length thereof.

The initial tension or stretching means, and the twisting means acting as a second-

ary tensioning means, may each be constructed in different forms and varied widely as to their structural characteristics; but in this invention it is preferred to employ a stretching means acting to grip the binder at two points and to apply strain to said binder by pulling it in two directions, whereas the twisting mechanism is positioned intermediate the two aforesaid gripping points, said twisting means being operable upon the crossing end portions of the binder for placing tension thereon intermediate the two spaced gripping points, whereby the binder is placed under the required tension.

Other functions and advantages of the invention will appear from the following description taken in connection with the drawings, wherein—

20 Figure 1 is a plan view of the implement in position for placing initial tension upon a binder.

Figure 2 is a side elevation of Figure 1.

25 Figure 3 is a vertical cross section in a plane intermediate the twisting mechanism and one of the stretching and gripping heads.

Figure 4 is an elevation partly in section of the twisting mechanism.

30 Figure 5 is a detail vertical section on the line 5—5 of Figure 3.

Figure 6 is a detail section of one of the grippers.

One embodiment of means for placing 35 tension initially on a wire binder is a stretcher comprising a plurality of heads A B, a double threaded screw spindle C, a guide stem D, a locating element E, and grippers F F' carried by the heads A B, respectively. Each head A or B is a single casting provided with a threaded aperture a and with a slot a' above the jaw b, said slot extending through the head as shown in Figure 6 for the binder to enter the slot

40 freely. The stem D passes loosely through the heads A B near the ends opposite the slotted jaws, said stem co-operating with the screw spindle in keeping the two heads in parallel relation. The guide stem D occupies a fixed relation to the slideable heads A

45 B and to the rotatory screw spindle, for which purpose the stem is fitted in an opening of the locating member E and is secured fixedly thereto in a suitable way, as by the cross-pin e. Said locating member is pro-

50 vided with a face plate e' in depending relation to the body portion of said member E, whereby the face plate is adapted to rest into contact with a side of the shipping pack-

60 age when the implement rests upon the top of said package, see Figure 2, and to thus act as means for locating said implement in a desired operative relation to the package for the application of the binder thereto.

65 The body portion of the locating member

is provided with an opening e², see dotted lines in Figures 1 and 2, through which loosely passes the screw spindle C, and to one end of said spindle is attached suitable means, such as the crank e, for imparting 70 rotary motion to said spindle. The spindle is provided with threads of opposite hand, said threads being of coarse pitch for imparting quick action to the spindle, and said threaded parts of the spindle are screwed 75 into the threaded openings a of the heads A B respectively, whereby the rotary motion of the screw journaled in the opening e² of the locating member acts to impart sliding movement to the heads A B, the two heads 80 being shifted simultaneously and in opposite directions to each other.

Each head A or B is slotted or forked by the provision of a recess f above the slot a', and within this recess is positioned the cam shaped head f' of one gripper F or F', see Figure 6. As shown, each gripper comprises a cam shaped head f' and a suitable handle which is shown in Figures 1 and 6 as extending upwardly from said head f'. The head f' of each gripper is provided with a rib g, whereas the jaw b of the head is provided with a groove g', see Figures 2 and 6, the rib g and the groove g' being in the same plane. The ribbed cam head contacts with the grooved underlying plate for crimping the wire binder, thus resulting in the formation of a shoulder. As shown, the two grippers act to produce shoulders at separated points on the wire binder, and these shouldered parts of the binder co-operate with tensioning means to preclude said wire binder from displacement or slipping under the strain applied to said wire in applying the desired tension thereto. A cross pin h passes through the recessed upper part f of the head A or B and through the head f' of the gripper, said pin h operating to pivotally attach the gripper to the sliding head and to serve as the fulcrum for 110 the gripper.

The twisting mechanism is positioned for operation upon the crossing end portions of the binder and at a point intermediate the sliding heads A B and their associated 115 grippers F F'. As shown, the operating parts of the twister are mounted in or carried by a non-sliding head composed of complementary parts G G' assembled into lateral contact with each other and secured firmly 120 together, as by bolts h'. The twister head is perforated for the passage through it of the guide stem and the screw spindle C, and said twister head is held against sliding movement by a binding screw h² mounted 125 in the rear part of the head and binding against the guide spindle, see Figures 3 and 4, whereby the twister head is fixedly retained in position intermediate the sliding heads A B and grippers F F'. 130

The operating elements of the twisting mechanism consist of a slotted gear H, a master gear I, and an intermediate gear J, said train of gears being encased within the 5 twister head and each gear being mounted in said head independently of the other gears of said train. The twister head is provided at its bottom edge with a jaw k and with a slot k' above said jaw, said slot 10 extending at one end through an edge of the twister head, see Figure 4 and dotted lines in Figure 3, in order that the crossing end portions of the binder may be received freely within the slotted part of the non-movable twister head. The complementary 15 parts G G' of the twister head are provided with interior recesses m in the plane of the slot k' to produce a bearing for the cylindrical body of the twister gear H, 20 whereby said twister gear is mounted for axial rotation within the twister head, see Figures 4 and 5. The body of the twister gear is provided with a longitudinal slot n, and in the normal position of the twister 25 gear H the slot n thereof is in register or alinement with the slot k' of the twister head, thus making provision for the free entry of the crossed portions of the binder into the slot of the twister head and into the 30 slot of the rotatory twister gear, see Figure 4.

The intermediate gear J is supported by a stub shaft j in appropriate bearings within the twister head so that said intermediate 35 gear is in mesh with the teeth of the twister gear H and with the teeth of the master gear I. Said master gear is on a shaft i mounted in bearings provided in the complementary parts G G' of the twister head, 40 and to this shaft there is secured an operating lever I' by a pin i', said lever I' being movable back and forth so as to apply power to the master gear, the movement of which master gear I is multiplied by the intermediate gear J for imparting the required rotative movement to the slotted twister gear H by a single movement of the lever I' in one direction.

For retaining the crossing or lapping end 45 portions of the binder within the slot k' of the twister head and the slot n of the twister gear, and to preclude said crossing binder ends from being thrown out of the twister gear by the rotatory motion thereof, I provide retainers, one at each side of the twister head, as shown at O P. Each retainer consists of an arm or plate positioned in close relation to one face of the twister head so as to extend across the slot k' therein 50 prior to imparting the rotary motion to the twister gear and at the period of rotation of the gear, but subsequently to the rotation of said gear, the retainers are shifted out of position, for which purpose the two retainers are mounted on a cross pin o, the latter 55 being journaled in the twister head at a point preferably above the gear H. As shown in Figure 5, the retainers are fitted on square portions of the cross pin and attached fixedly thereto by screws o', so that rocking 60 movement of the cross pin imparts swinging motion to the two retainers simultaneously. The retainers may have any desired form, but as shown in Figure 3 one retainer is provided with a lip p and with a finger piece p', the latter affording convenient means for moving the retainer and rotating the cross pin so that the two retainers are shifted into and out of position by the rotative movement 65 of the cross pin.

Having described the construction of the implement, the operation may be set forth as follows:—The implement is usually placed upon the top of a shipping package indicated at X, with the face plate e' of the locating member E in contact with a side of the package, and a binder, usually a wire Y, is looped around said package, the end portions y y' of the binder wire being in crossing relation, see Figure 1. The grippers F F' being in the opened (raised) positions (see Figure 6), one end y of the wire is passed in the slot a' and between the jaw b of head A and the gripper F, whereas the other end portion y' of the binder is received in the slot a' and between the jaw b of head B and gripper F', see Figures 1 and 2, the overlapping portions y y' of the wire passing loosely or freely within the slots k' n of the twister head G G' and the twister gear H, respectively. The grippers F F' are now turned for the ribs g thereof to crimp or bend the wire toward the grooves g' in the jaws of the respective heads A B, and thus shoulders are formed on the wire 105 at separated points, one at the head A and the other at head B, said points being separated relatively to the twisting mechanism. The shoulder or shoulders provided on the wire co-operate with one element or with both elements of the tensioning means, said shoulder of the wire and the element or elements co-operating to retain the wire 110 against displacement or movement with respect to said element or elements of the tensioning means during the operation of placing tension on said wire. The operator now turns the crank c, to rotate screw C, the latter acting to impart sliding movement to the heads A B for drawing them toward each other and toward the twisting mechanism. This operation imposes strain upon the major length of the wire by drawing the same in two directions around the shipping package X, whereby the required tension is initially placed upon the wire.

By drawing upon the wire in two directions at one operation of the tension means I have found that the wire is more quickly 120 and uniformly stretched around the package 125

and the several corners thereof, and by using the screw-actuated stretcher it is possible to apply such tension to the wire as to embed the latter in the material of the package, 5 particularly at the corners thereof, as shown in Figures 1 and 2, whereby it is not required to use separate fasteners for holding the wire against displacement, for the reason that the wire embedded in the corners 10 of the package is retained against movement relatively to the package.

The wire is thus placed under tension for the major part of its length around the package, but the lapping or crossing end 15 portions of said binder are not only free but they are spaced relatively to the top surface of the package, see Figure 2. The next step consists in the operation of the twister, but prior thereto the operator im- 20 parts movement to the cross pin σ for moving the retainers $O P$ across the ends of the slot k' in the twister head, so as to preclude the free ends of the binder from being thrown out of the head by the rotative 25 movement of the twister gear H .

Now, while the binder is held under tension by the heads $A B$ and screw C , the operator moves the lever I' in a forward direction, thus rotating gears $J I$ and imparting 30 rotative motion to the twister gear H , the latter acting to twist together the lapping or crossing end portions $y y'$ of the binder. The twisting of the binder ends $y y'$ places additional tension upon the binder at a 35 point intermediate the heads $A B$, and while the binder is under tension of the stretcher, and the effect of this operation is to lock the end portions of the binder by twisting them directly one to the other and to stretch 40 that part of the binder intermediate the gripping points at the two heads $A B$, thus imparting to the binder additional tension for taking up slack therein, the ultimate effect of which is to compensate for the slack 45 which might otherwise take place in the binder when the implement is removed, whereby the binder is so tensioned that there is no appreciable slack when the stretcher is disconnected and said binder remains 50 under tension around the package and in such frictional contact therewith as to compress the components of the package into the desired firm relation with a view to increasing the stability of said package.

55 During the twisting operation, the lapping portions of the wire are retained within the slot n of the gear H by the retainers $O P$, and this gear is turned the required number of times (say two) for completing the twist by a single motion of lever I' , at the end of which the gear H is in a position for the slot n therein to register with the slot k' of the twister head. The retainers $O P$ are now lifted by applying pressure 60 to the finger piece p' , and the grippers $F F'$

are released from contact with the binder, after which the implement is bodily shifted out of position relatively to the binder under tension, the slots $a' k'$ permitting the lateral withdrawal of the implement relatively to 70 the binder.

Having thus fully described the invention, what I claim as new and desire to secure by Letters Patent is:

1. In a package binding implement, binder-twisting means embodying a non-movable head provided with a binder receiving slot, a twister gear mounted in said head, said gear having a slot adapted for register with the slot of the head, means for imparting 80 rotative movement to said twister gear, and a plurality of retainers mounted on the head and shiftable relatively to the slot therein, in combination with binder tensioning means operable for initially placing tension upon 85 the binder and for retaining the latter under tension during the operation of said twisting means.

2. In a package binding implement, binder-twisting means embodying a non-movable 90 head provided with a binder-receiving slot, a cross pin mounted on the head for rocking movement therein, a plurality of retainers carried by the cross pin and shiftable relatively to the slot of said head, and a train 95 of gears journaled in said head, in combination with binder tensioning means including means for gripping a binder at opposite sides of the twister head and means for imparting movement to said gripping means relatively 100 to the twister head so as to place tension upon the binder prior to the action of the twisting means and to retain the binder under tension at the period of operation of the twisting means.

3. In a package binding implement, a twister-head provided with a binder receiving aperture, a binder retaining member supported by said head to frictionally hold the overlapped portions of the binder for pre- 110 cluding displacement therefrom of the crossing portions of a binder during the operation of twisting the same, said binder-retaining member being shiftable relatively to said binder-receiving aperture, and twisting 115 means carried by said twister-head.

4. In a package binding implement, a twister-head provided with a slot adapted for the reception of the crossing portions of a wire binder, a plurality of binder retaining 120 members supported by said twister-head and positioned one at each side of the twister-head for retaining in the slot thereof the crossing end portions of a binder during the operation of twisting the same, said binder-retaining members being shiftable relatively 125 to the binder receiving slot, and twisting means carried by the twister-head.

5. In a wire tying machine, tension means including a plurality of heads each provided 130

with means for deforming a wire binder and operable to grasp said deformed binder and to retain said binder against movement with reference to said head, and means for effecting a relative movement of said heads and operable subsequently to the deforming and grasping operations upon the binder, in combination with binder-joining means operable to unite portions of said binder, and retaining means engageable with the binder and effective during the action of said binder-joining means in precluding dislodgment of said binder with reference to the binder-joining means.

6. In a wire tying machine, tension means including a plurality of heads each provided with means for deforming a wire binder and for grasping said deformed binder, and means for effecting a relative movement of said heads whereby the binder is tensioned, combined with a twister head positioned

intermediate said relatively movable heads, binder-retaining means supported by the twister head and engageable with a binder at the respective sides of the twister head, 25 and twisting means mounted in the twister head for joining the end portions of said binder.

7. In a wire tying machine, tension means including a plurality of heads and means 30 for effecting a relative movement of said heads, a twister head positioned intermediate said relatively movable heads, a plurality of binder-retaining members supported by the twister head, and engageable with said 35 binder at opposite sides of the twister head, and twisting means mounted in said twister head.

In testimony whereof I have hereto signed my name this 17th day of February, 1921.

SPENCER C. CARY.
